CLAIM

The ornamental design for a combined accessory tray and book support for use in bath tubs, beds or the like, substantially as shown and described.

DESCRIPTION

FIG. 1 is a reduced front and top perspective view of a combined accessory tray and book support for use in bath tubs, beds or the like showing my new design; FIG. 2 is a side elevational view thereof, the opposite side being a mirror image;

FIG. 3 is a rear elevational view thereof;

FIG. 4 is a top plan view thereof;

FIG. 5 is a bottom plan view thereof.
